UNITED STATES PATENT OFFICE.

JAMES J. FULTON, OF GUERNEVILLE, CALIFORNIA.

CENTRIFUGAL CLOTHES-WASHING MACHINE.

1,345,761.

Specification of Letters Patent.

Patented July 6, 1920.

Application filed January 8, 1920. Serial No. 350,073.

To all whom it may concern:

Be it known that I, JAMES J. FULTON, a citizen of the United States, residing at Guerneville, in the county of Sonoma and State of California, have invented certain new and useful Improvements in Centrifugal Clothes-Washing Machines, of which the following is a specification.

This invention relates to washing machines, and more particularly to the centrifugal type of machine where a constant circulation of the water is obtained while the machine is in operation.

An object of the invention is to provide a suitable construction of washing machine, which may be highly geared to impart a high speed of rotation to the washing tank, so that the water will rise up the sides thereof, and overflow into the receiving or storage tank, to be used over again.

Another object is to provide a centrifugal washing machine which will do away with the customary beaters or agitators, thereby saving wear and tear on the clothes during the washing operation.

A further object is to provide a suitable centrifugal washing machine which will be easy to operate and inexpensive to manufacture.

Other objects will appear as the description proceeds.

With these and other objects in view, the invention, consisting in the combination, construction and novel arrangement of parts, will be fully understood from the following description, reference being had to the accompanying drawings, in which like characters of reference indicate like parts throughout the several views, in which,—

Figure 1 is a side elevation of my improved washing machine, partly broken away to show the interior construction, and

Fig. 2 is a plan view, partly broken away to show the several parts.

The machine is supported by legs or supporting members 1, which are braced by cross braces or members 2 and 3. Two of the supporting legs extend well above the others, as at 4, and are connected by a single cross member or beam 5.

A vertical rotatable shaft 6 is mounted through the members or braces 3 and 5, and is connected by means of a spider 7 to the basin or tub 8, which is to be revolved. A bevel gear 9 is carried on the shaft 6.

Bracket member 10 is attached to the under side of beam 5, and carries a set of high ratio gears 11 which are operated by hand crank 12 passing through one of the extended legs 4. This set of gears 11 is engaged by bevel gear 9, and, upon rotation of the hand crank 12 causes the tub 8 to revolve at a high rate of speed.

The tub 8 has its bottom open at the center and so formed as to provide a tubular well 65 or cylinder 13 which extends a considerable distance up into the inside of the tub. A short distance from the cylinder 13, and around the same is rigidly attached a perforated cylinder 14. Spaced from this cylinder 14 and around the same is rigidly attached a second perforated cylinder 15, which is of the same height as the cylinders 13 and 14, and is adjacent the bottom 16 of the inclined wall 17 of the tub 8.

Mounted upon suitable brackets 18 on the legs 1, is a circular tank 19, which surrounds the upper portion of the tub 8 and which has an inwardly extending flange 20 on the top of its outer wall. The top of the tub 8 is positioned slightly above and over the inner wall of the tank 19, as at 21.

A pipe 22 leads from the bottom of the tank 19 down to the bottom of, and under the tub 8 and thence up through its center 85 and over the cylinder 13. A smaller perforated section of pipe 23 is connected on to the pipe 22 by a union or joint 24 and extends down between the cylinders 13 and 14.

When it is desired to operate the machine, 90 the soiled clothes are placed between the two perforated cylinders or walls 14 and 15, and the tank 19 filled with water. If desired, a small amount of water may be placed in the tub also.

It will be seen that by turning the crank 12, the tub 8 will revolve at a very high rate of speed. The water from the tank will pass through pipe 22 and spray through pipe 23 over the clothes and into the tub. The 100 high speed of rotation of the tub will cause the water therein to swirl around its inclined sides, and by centrifugal action, to overflow into the tank 19. Therefore, it is evident that there will be a continuous changing or 105 circuit of water through the clothes.

The same operation may also be gone through for rinsing and bluing the clothes.

After the various operations are completed, the water may be drained from the 110

tank and tub, by means of cocks 25 and 26 respectively. A pet cock 27 is employed for cutting off the flow of water from the tank to the tub.

5 Many minor changes in detail of construction may be resorted to without departure from the spirit of the invention.

Having thus described my invention what I claim as new and desire to secure by Letters Patent of the United States is:

10 1. A washing machine comprising supporting members, a tub mounted for rotation carried by said members, high speed gearing mounted on said members and connected to operate said tub, said tub having its bottom formed with an inwardly and upwardly extending tubular collar centrally thereof, a supply tank positioned adjacent to and around the upper portion of said tub, 15 and means connected to the tank which passes below the tub and up through the central collar into the tub, whereby the water will spray into said tub.

20 2. A washing machine comprising supporting members, a tub mounted for rotation carried by said members, an imperforate wall forming a cylinder in the center of said tub, a plurality of perforated cylinders around said first named cylinder, a tank 25 surrounding the upper portion of said tub, and means for carrying the water from said tank up through said central cylinder into the tub.

25 3. A washing machine comprising a frame, a revolvably mounted imperforate tub, a cylindrical wall in the center of said tub, a plurality of perforated walls around said first wall and spaced therefrom and from each other, a tank surrounding said 30 tub, and means for carrying the water from said tank through the bottom of and into said tub.

4. A washing machine comprising a frame, a tub revolvably mounted therein, a wall forming a cylinder in the center of said tub, a plurality of perforated walls around said first named wall and spaced therefrom and from each other, a tank surrounding said tub, and means for carrying the water from the tank up through the central cylinder of said tub. 45

5. A washing machine comprising a frame, a revoluble tub mounted in said frame, said tub having an inclined wall, a cylindrical wall within said tub, a plurality of perforated walls surrounding said cylindrical wall, and spaced therefrom and from each other, a tank surrounding the upper portion of said tub, and means for carrying the water from the tank up through the 50 central cylindrical wall. 55

6. A washing machine comprising a frame, a tub rotatably mounted therein, a central wall formed in said tub, a plurality of spaced perforated walls around said central wall, a tank surrounding the upper portion of said tub, means connected with said tank extending below said tub and up through said central wall, and down between said central wall and the adjacent 60 perforated wall, whereby there will be a continuous circuit of the water. 65

7. A washing machine comprising supporting members, a tub mounted for rotation carried by said members, a wall forming a cylinder in the center of said tub, a plurality of perforated cylinders around said first named cylinder, a tank surrounding the upper portion of said tub, and drainage means connecting said tank with said 75 tub. 80

In testimony whereof I affix my signature.

JAMES J. FULTON.
